(57) CLAIM

The ornamental design for a candy dispensing machine, as shown and described.

DESCRIPTION

FIG. 1 is a front elevation view of the candy dispensing machine showing my new design;

FIG. 2 is a left side elevation view thereof;

FIG. 3 is a top plan view thereof;

FIG. 4 is a rear elevation thereof;

FIG. 5 is a right side elevation view thereof;

FIG. 6 is a bottom plan view thereof; and,

FIG. 7 is an enlarged exploded view of the central portion thereof, shown separately for clarity of illustration.
